DELAY PLUNGER ASSEMBLY FOR ARTILLERY
TYPE FUSES

Robert P. Marshall, Falls Church, Va.

Application July 15, 1953, Serial No. 368,240

5 Claims. (Cl. 102—76)

(Granted under Title 35, U. S. Code (1952), sec. 266)

The invention described herein may be manufactured and used by or for the Government for governmental purposes without the payment to me of any royalty thereon.

The present invention relates generally to fuses, and more particularly to an impact responsive delay plunger assembly.

In the type of fuses which are provided with a delay plunger assembly having a stationary firing pin and a movable plunger it is usual to lock the movable plunger until the projectile is in flight so that on impact the movable plunger may be forced through inertia to contact the stationary firing pin. If the plunger is unrestrained it may creep forward under its own weight to contact the stationary element and explode the shell in flight, or if held in the unarmed position until impact, one or all of the locking members may be driven back to a safe position to effectually prevent movement of the plunger and thus render the fuse inoperative.

It is therefore a primary object of the invention to provide a delay plunger assembly increasing the sensitivity of inertia delay functioning of the fuse.

Accordingly it is an object of the invention to provide a delay plunger assembly having a variable strength locking device allowing only a limited creep of the plunger during air travel.

A further object is to simplify structural features and reduce to a minimum number the parts employed, to the end that the delay plunger assembly may be manufactured at low cost and the parts readily assembled and effectively retained in the prepared safety condition prior to firing.

A practical embodiment of the invention as applied to an artillery point detonating fuse is illustrated in the accompanying drawings, wherein:

Figure 1 is a fragmentary longitudinal sectional view of a fuse showing a delay plunger assembly constructed in accordance with the invention;

Figure 2 is a cross section taken along the line 2—2 of Figure 1.

Figure 3 is a fragmentary sectional view showing one of the spring urged locking detents in locking position;

Figure 4 is a sectional view showing the position of the plunger after impact.

Referring more particularly to the drawings in which like reference numerals refer to like parts throughout the different views, 1 designates a point detonating fuse threaded at 2 for attachment to a projectile 3. The head of the fuse is provided with a super quick detonating element 4. The flash tube 5 extends from the detonating element 4 to a chamber 10 formed in the fuse body. The bore of the flash tube is normally obstructed by a transverse spring urged setting plunger 8 which acts as a safety device and which moves outwardly under the influence of centrifugal force during flight. The plunger can be set for super quick firing action in which it moves outwardly or for delay action in which the plunger is locked in its obstructing position.

2

Mounted in the fuse body chamber 10 is the delay plunger assembly which will now be described in detail. Lining the upper portion of the cavity is a cup shaped liner 14 having an aperture 24 registering with the flash tube bore. An annular detent housing 15 which is mounted in an offset portion of the chamber 10 surrounds and extends below the cup shaped liner. The liner rests on an inner annular shoulder 25 formed in the upper portion of the detent housing. Slidably mounted in the detent housing and liner is a cylindrical plunger 9 which is centrally bored to form a flash duct 6 in registry with the flash tube 5 and extends between the flash tube and the booster charge 7. The undersurface of an annular offset portion 26 of the plunger bears on the upper surface of the shoulder of the detent housing. A detonating element 12 is mounted in the plunger to one side of the flash duct 6 and is in alignment with a firing pin 13 located on the inner surface of the liner.

The portion of the plunger below the liner contains three outwardly opening cavities 19 spaced 120 degrees apart. The detent housing contains three similar bores 16 which are in radial alignment with the cavities. The bores 16 each contain locking detents 17 which are urged into the cavities by springs 18. A ball 20 is disposed in each of the cavities and normally held against the inner end of the cavity by the spring urged detents.

To keep the plunger 9 in proper alignment so that the detonating element 12 will be fired by the pin 13, and the bores 16 and cavities 19 will be in registry, the outer end of a guide pin 21 provided in a radial bore 22 in the plunger body, projects into a longitudinal slot 23 in the cup shaped liner 14.

Functioning of the device is as follows: No action will take place until sufficient rotational speed has been established so that centrifugal force overcomes the resistance of the springs 18 and the spring of the setting plunger 8. The setting plunger will then move outwardly to open the passageway of tube 5 communicating from the point detonating element to the booster. Detents 17 will also be urged outwardly causing the balls 20 to assume a position where their centers will be somewhat within the periphery of the plunger element 9. The device is now in unlocked or armed position. The plunger 9 may creep forward for a limited distance, the creep being limited by the forward edges of the bores 16 contacting the surfaces of the three balls 20. In the event that rotation of the round decreases to the extent of allowing the strength of the locking detent springs 18 to overcome centrifugal force, the detents will be prevented from entering the cavities 19 as the plunger 9 has moved forward a sufficient distance to obstruct the return of the locking detents as the bores 16 and cavities 19 are now out of register.

Upon impact, the super quick action element 4 will detonate the booster 7. However, should the super quick action fail, the shell will function with delay action rather than become a dud. Also, the setting plunger 8 can be locked in position so as to obstruct the flash tube 5 and only the delay plunger assembly will function to detonate the booster. As seen best in Figure 4, the plunger element 9 will be driven forward upon impact causing the balls 20 to be cammed into the cavities 19 in the plunger thus freeing the plunger 9 to move in its forward position bringing the detonator element 12 against the firing pin 13 thus firing the shell. Detonating element 12 is always held in alignment with the firing pin 13 due to the slot 23 and pin 21.

Thus it is seen that a plunger element has been devised, more positive in action, economical in manufacture and easily adapted to replacement of existing parts.

While a specific embodiment of the invention has been shown and described, it will be understood that various

alterations may be made without departing from the spirit of the invention as indicated in the appended claims.

I claim:

1. In a detonating fuse the combination comprising a body member, a chamber formed in said body member, a delay plunger longitudinally slideable in said chamber, a detonator carried by said plunger, a firing pin fixed in said body and in normally spaced relation with said detonator, and detent means to maintain said plunger against appreciable forward creep during projectile flight, said means comprising a plurality of circumferentially spaced radial cavities formed in said plunger, a plurality of circumferentially spaced radial bores formed in said body in radially axial registry with said cavities, a ball movable in each passage formed by the registry of respective bores and cavities, and a spring pressed detent in each bore normally urging said ball into its respective cavity, said spring pressed detent yielding to centrifugal force to permit radial ball motion to a position in part within said respective bore whereby said plunger will creep to a limited degree until motion is arrested by engagement between said ball and said bore.

2. In a detonating fuse the combination comprising a body member, a chamber formed in said body member, a delay plunger coaxially disposed and longitudinally slideable in said chamber, a detonator carried by said plunger, a firing pin fixed in said body and in normally spaced relation with said detonator, and detent means to maintain said plunger against appreciable longitudinal creep during projectile flight, said detent means comprising a plurality of circumferentially spaced radial bores formed in said body and opening into said chamber, a plurality of circumferentially spaced radial cavities formed in said plunger and opening into the outer surface thereof in axially aligned communication with said bores, a ball disposed in each passage formed by respective bores and cavities and a spring pressed pin in said bore normally urging said ball radially inward into said cavity and yielding to centrifugal force whereby said ball advances radially during projectile flight in part at least within said bore and limited plunger motion is allowed.

3. In a percussion fuze for a spin type projectile the combination comprising a body member having a first radial bore, a chamber formed in said body, a firing pin in said chamber, a delay action plunger slideable in said chamber and having a second radial bore coaxial with said first bore, there being a detonator in said plunger in axial alignment with said firing pin, centrifugally operated spring pressed detent means in said first bore for locking said plunger in normal safe position, and ball means in said second bore and projected partly into said first bore under the influence of centrifugal force, holding said plunger for limited creep during flight of the projectile and releasing said plunger on impact for forward movement to ignite said detonator, when forward inertia of the projectile ceases,

4. In a percussion fuze for a spin type projectile the combination comprising a body member, a chamber formed in said body member, a rearwardly extending firing pin in the forward end of said chamber, a delay action plunger axially slideable in said chamber, there being a detonator in said plunger in axial alignment with said firing pin, said plunger having a first radial bore in its periphery, a fixed annular detent housing surrounding said plunger and having a second radial bore therein in axial registry with the first bore, a spring pressed detent in the second bore and pressed into the first bore to lock said plunger to said annular detent housing in normal safe position, and a ball in the first radial bore inwardly of said detent, limiting radially inward movement of said plunger to a position in which its greater portion remains within the first radial bore during flight of the projectile.
5. In a percussion fuze for a spin type projectile the combination comprising a body member, a chamber formed in said body member, a rearwardly extending firing pin in the forward end of said chamber, a delay action plunger axially slideable in said chamber, there being a detonator in said plunger in axial alignment with said firing pin, said plunger having a first radial bore in its outer periphery, a fixed annular detent housing surrounding said plunger and having a second radial bore therein in axial registry with the first bore, a spring pressed detent in the second radial bore and extending into the first radial bore to lock said plunger to said annular detent housing in normal safe position, and a ball in the first radial bore inwardly of said detent limiting radially inward movement of said plunger to a position in which its greater portion remains within the first radial bore during flight of the projectile, the outer surface of the lesser portion of said ball engaging the forward wall of said second radial bore to effect limited forward creep of said plunger in flight and to release said plunger on impact with a target when said ball is cammed inwardly by the said forward wall when residual forward energy in said plunger overcomes centrifugal energy in said ball.
20. In a percussion fuze for a spin type projectile the combination comprising a body member, a chamber formed in said body member, a rearwardly extending firing pin in the forward end of said chamber, a delay action plunger axially slideable in said chamber, there being a detonator in said plunger in axial alignment with said firing pin, said plunger having a first radial bore in its outer periphery, a fixed annular detent housing surrounding said plunger and having a second radial bore therein in axial registry with the first bore, a spring pressed detent in the second radial bore and extending into the first radial bore to lock said plunger to said annular detent housing in normal safe position, and a ball in the first radial bore inwardly of said detent limiting radially inward movement of said plunger to a position in which its greater portion remains within the first radial bore during flight of the projectile, the outer surface of the lesser portion of said ball engaging the forward wall of said second radial bore to effect limited forward creep of said plunger in flight and to release said plunger on impact with a target when said ball is cammed inwardly by the said forward wall when residual forward energy in said plunger overcomes centrifugal energy in said ball.
25. In a percussion fuze for a spin type projectile the combination comprising a body member, a chamber formed in said body member, a rearwardly extending firing pin in the forward end of said chamber, a delay action plunger axially slideable in said chamber, there being a detonator in said plunger in axial alignment with said firing pin, said plunger having a first radial bore in its outer periphery, a fixed annular detent housing surrounding said plunger and having a second radial bore therein in axial registry with the first bore, a spring pressed detent in the second radial bore and extending into the first radial bore to lock said plunger to said annular detent housing in normal safe position, and a ball in the first radial bore inwardly of said detent limiting radially inward movement of said plunger to a position in which its greater portion remains within the first radial bore during flight of the projectile, the outer surface of the lesser portion of said ball engaging the forward wall of said second radial bore to effect limited forward creep of said plunger in flight and to release said plunger on impact with a target when said ball is cammed inwardly by the said forward wall when residual forward energy in said plunger overcomes centrifugal energy in said ball.
30. In a percussion fuze for a spin type projectile the combination comprising a body member, a chamber formed in said body member, a rearwardly extending firing pin in the forward end of said chamber, a delay action plunger axially slideable in said chamber, there being a detonator in said plunger in axial alignment with said firing pin, said plunger having a first radial bore in its outer periphery, a fixed annular detent housing surrounding said plunger and having a second radial bore therein in axial registry with the first bore, a spring pressed detent in the second radial bore and extending into the first radial bore to lock said plunger to said annular detent housing in normal safe position, and a ball in the first radial bore inwardly of said detent limiting radially inward movement of said plunger to a position in which its greater portion remains within the first radial bore during flight of the projectile, the outer surface of the lesser portion of said ball engaging the forward wall of said second radial bore to effect limited forward creep of said plunger in flight and to release said plunger on impact with a target when said ball is cammed inwardly by the said forward wall when residual forward energy in said plunger overcomes centrifugal energy in said ball.
35. In a percussion fuze for a spin type projectile the combination comprising a body member, a chamber formed in said body member, a rearwardly extending firing pin in the forward end of said chamber, a delay action plunger axially slideable in said chamber, there being a detonator in said plunger in axial alignment with said firing pin, said plunger having a first radial bore in its outer periphery, a fixed annular detent housing surrounding said plunger and having a second radial bore therein in axial registry with the first bore, a spring pressed detent in the second radial bore and extending into the first radial bore to lock said plunger to said annular detent housing in normal safe position, and a ball in the first radial bore inwardly of said detent limiting radially inward movement of said plunger to a position in which its greater portion remains within the first radial bore during flight of the projectile, the outer surface of the lesser portion of said ball engaging the forward wall of said second radial bore to effect limited forward creep of said plunger in flight and to release said plunger on impact with a target when said ball is cammed inwardly by the said forward wall when residual forward energy in said plunger overcomes centrifugal energy in said ball.
40. In a percussion fuze for a spin type projectile the combination comprising a body member, a chamber formed in said body member, a rearwardly extending firing pin in the forward end of said chamber, a delay action plunger axially slideable in said chamber, there being a detonator in said plunger in axial alignment with said firing pin, said plunger having a first radial bore in its outer periphery, a fixed annular detent housing surrounding said plunger and having a second radial bore therein in axial registry with the first bore, a spring pressed detent in the second radial bore and extending into the first radial bore to lock said plunger to said annular detent housing in normal safe position, and a ball in the first radial bore inwardly of said detent limiting radially inward movement of said plunger to a position in which its greater portion remains within the first radial bore during flight of the projectile, the outer surface of the lesser portion of said ball engaging the forward wall of said second radial bore to effect limited forward creep of said plunger in flight and to release said plunger on impact with a target when said ball is cammed inwardly by the said forward wall when residual forward energy in said plunger overcomes centrifugal energy in said ball.
45. In a percussion fuze for a spin type projectile the combination comprising a body member, a chamber formed in said body member, a rearwardly extending firing pin in the forward end of said chamber, a delay action plunger axially slideable in said chamber, there being a detonator in said plunger in axial alignment with said firing pin, said plunger having a first radial bore in its outer periphery, a fixed annular detent housing surrounding said plunger and having a second radial bore therein in axial registry with the first bore, a spring pressed detent in the second radial bore and extending into the first radial bore to lock said plunger to said annular detent housing in normal safe position, and a ball in the first radial bore inwardly of said detent limiting radially inward movement of said plunger to a position in which its greater portion remains within the first radial bore during flight of the projectile, the outer surface of the lesser portion of said ball engaging the forward wall of said second radial bore to effect limited forward creep of said plunger in flight and to release said plunger on impact with a target when said ball is cammed inwardly by the said forward wall when residual forward energy in said plunger overcomes centrifugal energy in said ball.
